UNITED STATES PATENT OFFICE

161,365

CHILD'S BIBBED SHIRT

Alex M. Parker, Hackensack, N. J.

Application May 9, 1950, Serial No. 9,827

Term of patent 14 years

(CL. D3—25)

To all whom it may concern:

Be it known that I, Alex M. Parker, a citizen of the United States of America, residing in Hackensack, county of Bergen, and State of New Jersey, have invented a new, original, and ornamental Design for a Child's Bibbed Shirt, of which the following is a specification, reference being had to the accompanying drawing, forming part thereof, wherein,

I claim:

The ornamental design for a child's bibbed shirt, substantially as shown.

ALEX M. PARKER.
